Primary Examiner — Mimosa De(74) *Attorney, Agent, or Firm* — QuickPatents, Inc.; Kevin Prince(57) **CLAIM**

I claim the ornamental design for a wig chiffarobe cabinet, as shown and described.

DESCRIPTION

FIG. 1 is a perspective view of a wig chiffarobe cabinet, showing my new design in a closed position;
FIG. 2 is a left-side elevational view thereof;
FIG. 3 is a front elevational view thereof;
FIG. 4 is a right-side elevational view thereof;
FIG. 5 is a rear elevational view thereof;
FIG. 6 is a bottom plan view thereof;
FIG. 7 is a top plan view thereof;
FIG. 8 is a perspective view thereof, showing both doors open;
FIG. 9 is a front elevational view of FIG. 8; and,
FIG. 10 is a left-side elevational view of FIG. 8, the right-side elevational view being a mirror image thereof.
The broken lines showing mannequines and wigs in FIG. 8 depict environmental matter and form no part of the claimed design.
